UNITED STATES PATENT OFFICE.

BENJAMIN M. GRIFFITH, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

FIRE-EXTINGUISHER.

1,243,733.

Specification of Letters Patent. Patented Oct. 23, 1917.

Application filed March 6, 1914. Serial No. 322,860.

To all whom it may concern:

Be it known that I, BENJAMIN M. GRIFFITH, a citizen of the United States, and resident of Pittsburgh, in the county of Allegheny and State of Pennsylvania, have invented certain new and useful Improvements in Fire-Extinguishers, of which the following is a specification.

One object of this invention is to provide 10 a compact portable fire extinguisher with improved means for storing and delivering compressed air to the fluid container for discharging the chemical when the extinguisher is in use. The invention is preferably embodied in a cylindrical tank-like structure which is partitioned to provide an air compartment or chamber beneath the fluid chamber, and a further purpose is to 15 so construct the cylinder or shell as to provide an external cavity in which the valve for controlling communication between the air and fluid chambers is located and protected.

A further purpose is to provide improved 20 pump means for charging the air chamber, together with an improved removable valve connection at the exterior of the cylinder or casing for establishing communication between the pump and air chamber.

Another object of the invention is to so 25 arrange the chemical discharge tube as to cause it to always project into the lowest portion of the bottom of the chamber and thereby cause all of the contents of the chamber to be emptied.

In the accompanying drawings, Figure 1 30 is a vertical section of a portable fire extinguisher constructed in accordance with and embodying the several improvements of the present invention. Fig. 2 is a sectional plan 35 on line 2—2 of Fig. 1. Fig. 3 is an enlarged sectional detail of the detachable valve connection between the pump and the air chamber.

Referring to the drawings, the cylindrical body or shell of the extinguisher is partitioned between its ends at 2 to separate the upper or main chamber 3 which holds the fluid chemical from air chamber 4 at the 40 lower end of the body. The top or crown 5 of chamber 3 is provided with a valved outlet 6 to which the fluid discharge tube 7 is connected by the ball and socket joint 8. Tube 7 reaches nearly to the bottom of chamber 3, i. e., partition 2, and by means of the

ball and socket joint the lower or inlet end of the tube gravitates to the lowest portion of chamber 3 when the extinguisher is held in inclined position, thereby insuring complete draining of the contents of the chamber. This movement of tube 7 may be facilitated by weighting the free portion thereof, as indicated at 9.

The body or shell of the extinguisher is contracted circumferentially, preferably in 60 the plane of partition 2 as indicated at 10, and the purpose of the external depression or recess thus formed in the body is to provide space in which certain operative parts may be located and protected from injury 65 and at the same time be readily accessible. Depression 10 is bridged by a pipe 11 which connects air chamber 4 with the upper portion of chemical chamber 3, and a valve 12 for this pipe is located in depression 10 and is thereby protected although conveniently 70 accessible.

Air chamber 4 is charged initially through inlet valve 13 located in the upwardly arched bottom 14, and if, due to long standing or other cause, the air pressure becomes depleted, a hand pump is provided for replenishing the same. The pump here shown is of the usual cylinder and piston type, the pump cylinder 15 being arranged within and extending longitudinally of chamber 3 and outwardly through crown 5 while its lower end extends into depression 10, as indicated at 15'. 16 is the plunger, 17 the plunger rod, and 18 the operating handle which is located at the top of the extinguisher body and in position for convenient manipulation with the body standing upright on the floor or other support.

With the pump thus located it is entirely 95 out of the way, no portion thereof projecting in such manner as to cause the extinguisher to occupy needless room. Also, with the pump located as described the body depression 10 provides space for the outwardly removable connection between the pump cylinder and air chamber 4, this connection being in the form of a fitting 19 which at its upper end is connected by union 20 with pump cylinder extremity 15', and at its lower end by union 21 with inlet tube 22 secured in the wall of chamber 4. Within fitting 19 is the check valve 23, past which air is forced by the pump into the air chamber. This valve is of usual tire valve con- 100 105 110

struction for which no novelty is claimed, excepting as located in fitting 19, and thus readily removable and accessible as may be necessary for adjustment or repair.

5. The operation of portable fire extinguishers of this general class is so well understood as to require little description. Chamber 3 is charged with a suitable fluid chemical, for instance tetrachlorid, and chamber 4 is charged through inlet 13 with air under suitable pressure. When the extinguisher is to be put into service, valve 12 is opened thereby admitting compressed air to the top of the fluid body in chamber 3 and forcing 15 the fluid out through tube 7. Inclination of the extinguisher body in any direction causes the discharge end of tube 7 to move to the lowermost part of chamber 3 and thus insure complete draining of its contents. If 20 through long standing the air pressure in chamber 4 becomes depleted, or if from any cause it is insufficient to discharge all of the chemical in an efficient manner, the pressure may be immediately replenished by the air 25 pump. Also, the pump is available for replenishing the air pressure at intervals if it is desired to take the precaution to maintain the extinguisher in a fully efficient condition regardless of lapse of time, this with- 30 out removing it from the position or station where it is kept ready for use.

I claim:

1. A portable fire extinguisher consisting of a tank provided with two chambers arranged one above the other with the uppermost chamber adapted to contain a fire extinguishing fluid and the lowermost chamber adapted to contain air under pressure, the tank formed between its ends with an external indentation, a discharge tube for the fluid chamber open to the lower portion of the latter, an air inlet for the air chamber, and a valved tube bridging the indentation and extending from the air chamber to the upper portion of the fluid chamber.

2. A portable fire extinguisher comprising a tank partitioned to form an air chamber at one end and a chamber for a fire extinguishing fluid at its opposite end, the tank formed between its ends with an external indentation, a pipe bridging the indentation and connecting the two chambers, and a valve for the pipe with said valve located in the tank indentation.

3. A portable fire extinguisher comprising a tank partitioned between its ends to form

an air chamber at its lower end and a chamber at its upper end for confining a fire extinguishing fluid, the tank indented externally between its ends, a pipe bridging the indentation and extending from the air chamber to the upper portion of the fluid chamber, a valve for the pipe with said valve located in the tank indentation, an outlet for the fluid chamber, and a tube extending from the outlet into close proximity to the bottom of the fluid chamber.

4. A portable fire extinguisher comprising a tank having an air chamber at one end and a chamber at its opposite end for confining a fire extinguishing fluid, an air pump located within the fluid chamber and operative from the exterior thereof, the tank formed with an external depression, and a connection between the pump and the air chamber with the connection bridging said depression.

5. A portable fire extinguisher comprising a tank having an air chamber at one end and a chamber at its opposite end for confining a fire extinguishing fluid, an outlet for the fluid chamber, an air pump within the fluid chamber and operative from the exterior thereof, the tank formed with an external depression, a fitting removably bridging the depression and adapted to connect the air pump with the air chamber, a check valve carried by the fitting, an outlet for the fluid chamber, and means for passing air from the air chamber to the fluid chamber.

6. A portable fire extinguisher comprising a tank partitioned between its ends to form an air chamber at its lower end and a chamber at its upper end for confining a fire extinguishing fluid, an outlet for the fluid chamber, means for passing air from the air chamber to the fluid chamber, the tank formed with an external depression, a pump cylinder within the fluid chamber with the lower end of the cylinder open in the tank depression, a plunger for the pump cylinder operative from the exterior of the tank, a fitting removably entered in the tank depression for connecting the lower end of the pump cylinder with the air chamber, and a check valve carried by the fitting.

In testimony whereof I affix my signature in presence of two witnesses.

BENJAMIN M. GRIFFITH.
